UNITED STATES PATENT OFFICE.

CHARLES WILLIAM THOMPSON, OF QUINCY, MASSACHUSETTS, ASSIGNOR OF ONE-HALF TO EDWIN J. TUCKER, OF MALDEN, MASSACHUSETTS.

PRESERVING RECEPTACLE.

Application filed January 29, 1921. Serial No. 440,804.

To all whom it may concern:

Be it known that I, CHARLES WILLIAM THOMPSON, a citizen of the United States, residing at Quincy, in the county of Norfolk and State of Massachusetts, have invented new and useful Improvements in Preserving Receptacles, of which the following is a specification.

This invention relates to a preserving receptacle having a cover adapted to confine a compressible gasket upon the mouth of the receptacle and form an air-tight closure, the receptacle and cover being of suitable rigid material such as glass.

The invention is embodied in the improvements hereinafter described and claimed, whereby a receptacle is provided adapted to be quickly and conveniently closed air-tight, and opened to expose the contents of the receptacle.

Of the accompanying drawings forming a part of this specification,—

Figure 1 is a side elevation of a receptacle embodying the invention, the lower portion being broken away.

Figure 2 is a section on line 2—2 of Figure 1.

Figure 3 is a top plan view.

Figures 4 and 5 are fragmentary views similar to portions of Figure 2, showing one of the clamps in different positions.

Figure 6 is a perspective view of one of the clamps shown by the preceding figures.

The same reference characters indicate the same parts in all of the figures.

In the drawings, 12 represents a receptacle, which may be formed as a jar or tumbler of greater diameter at the top than at the bottom, although this form is not essential.

Below the upper end or mouth of the receptacle is a downwardly facing shoulder 13, against which a band 14 is confined against upward movement, said band being preferably formed from a length of wire, the ends of which are twisted together at 15. 16 represents the cover which is formed to be seated on a compressible gasket 17, seated on the mouth or upper end of the receptacle. The cover is provided on its upper side with an annular ridge 18, the crown of which is raised above the portion of said upper side within the ridge. Pivoted and anchored on the receptacle by means of the band 14 are two resilient cover-confining clamps, which include jaws formed to swing

across and be upwardly displaced by the ridge 18, as indicated by Figure 5, and adapted, after crossing the crown of the ridge, to exert a clamping pressure on the cover at the inner side of the ridge.

Each resilient clamp is formed from a length of wire bent as clearly shown by Figure 6, to form terminal eyes 19, embracing and adapted to turn on the band 14, lower arm portions 20 formed in part by 65 spring loops 20^a, and formed to extend from the band 14 across the margin of the cover, and upper arm portions 21, extending inward at an angle to the lower portions 20, and curved to form jaws, adapted to extend 70 across the ridge 18, and bear on the cover at the inner side of the ridge when the clamps are closed on the cover, as shown by Figure 2. The upper arm portions or jaws are connected by a neck 22. When the clamp is 75 displaced or swung outwardly from its closed operative position, as shown by Figure 4, the loops 20^a are expanded so that the lower arm portions are contracted lengthwise, and the jaws 21 are relatively near the band 14, the 80 lower portions of the jaws being considerably below the crown of the ridge 18. Considerable inward pressure is therefore necessary to move the clamp to the operative closed position shown by Figure 2. This 85 pressure is exerted on the arm portions 20, and first causes an upward displacement of the jaws 21, as indicated by Figure 5, the loops 20^a being thus contracted, so that the arm portions 20 are elongated lengthwise 90 and put under increased tension.

When the lower portions of the jaws are moved across the crown of the ridge, the increased tension of the wire causes the jaws to exert a clamping pressure on the cover at 95 the inner side of the ridge, the arrangement being such that the cover prevents the jaws from springing downward to their normal positions, so that they continuously exert a clamping pressure on the cover.

When the jaws are in their operative positions, the ridge 18 opposes outward movement of the jaws, so that considerable outward pressure is required to displace the jaws and release the cover, this pressure being exerted on the necks 22, which are conveniently located above the top surface of the cover.

The loops 20^a constitute auxiliary or reinforcing springs, which yieldingly contract 110

- the lower arm portions 20 lengthwise, and exert an effective clamping pressure, through the jaws, on the cover, in addition to the pressure caused by the resilience of the jaws.
- 5 When the clamps are being forced to their closed positions, the jaws first slide across the ridge and are upwardly displaced thereby, and then spring downward to clamp the cover and engage the inner side of the ridge.
- 10 I claim:
- The combination with a receptacle, and a cover therefor having an annular marginal ridge on its upper surface; of a pair of clamps adapted to be closed on the cover, 15 each composed of a length of resilient wire bent to form lower arm portions, which are pivotally anchored to the receptacle, upper arm portions extending inward at an angle with the said lower portions, and curved to 20 form jaws, adapted to extend across said
- ridge and bear on the cover at the inner side of the ridge when the clamps are closed, and a neck connecting the upper arm portions, the lower arm portions being composed in part of spring loops, which yieldingly contract said portions lengthwise and constitute reinforcing springs adapted to exert an effective clamping pressure, through the jaws, on the cover, in addition to the pressure caused by the resilience of the jaws, said 30 jaws being adapted to slide across the ridge when the clamps are being forced to their closed positions, and to spring downward to clamp the cover and engage the inner side of the ridge when the clamps are fully 35 closed.

In testimony whereof I have affixed my signature.

CHARLES WILLIAM THOMPSON.
